UNITED STATES PATENT OFFICE.

MORRIS P. BRAY, OF NEW HAVEN, CONNECTICUT.

STAY FOR CORSETS.

SPECIFICATION forming part of Letters Patent No. 231,894, dated September 7, 1880.

Application filed June 19, 1880. (No model.)

To all whom it may concern:

Be it known that I, MORRIS P. BRAY, of New Haven, in the county of New Haven and State of Connecticut, have invented a new

5 Improvement in Stays for Corsets; and I do hereby declare the following, when taken in connection with the accompanying drawings and the letters of reference marked thereon, to be a full, clear, and exact description of the same, and which said drawings constitute part 10 of this specification, and represent, in—

Figure 1, perspective view of the stay as prepared for introduction in the corset, enlarged; Fig. 2, transverse section of part of 15 a corset, showing the stay inserted, enlarged.

This invention relates to an improvement in corsets and stays therefor, the object being to produce a serviceable and durable stay as a substitute for whalebone.

20 To this end the invention consists in a strip of rawhide introduced between the thicknesses of the corset parts with lines of stitches run through the said parts and through the strip of rawhide, whereby the rawhide stays are secured in place in the process of manufacture 25 of the corset.

In the preparation of the stay, a strip is cut from rawhide, and channels *a* cut in one or both surfaces, so as to materially reduce the thickness where said channels are cut.

A stay thus produced is introduced between the two thicknesses of the corset parts, as seen in Fig. 2; then lines of stitches *d* are run through the parts and through the reduced thickness of the stay. The channels or reduction of thickness of the stay permits the needle to pass more easily through than if the full thickness were retained.

The rawhide has an elasticity quite equal to the whalebone, will not break, and avoids the necessity of preparing pockets for the stays prior to insertion, as in the case of bone and similar material. At the same time the rawhide is very much cheaper than bone.

I claim—

25 A stay for corsets, consisting of a strip of rawhide with channels cut therein, substantially as described.

MORRIS P. BRAY.
